[57] CLAIM

The ornamental design for a combined punch and binding machine, as shown.

DESCRIPTION

FIG. 1 is a front elevational view of a combined punch and binding machine showing my new design;
FIG. 2 is a right side elevational view of the machine;
FIG. 3 is a left side elevational view of the machine from the opposite side of FIG. 2;
FIG. 4 is a rear elevational view of the machine;
FIG. 5 is a top plan view of the machine; and
FIG. 6 is a bottom plan view of the machine.

FIG.1

FIG.2

FIG.3

FIG.4

FIG.5

FIG. 6
